UNITED STATES PATENT OFFICE.

OSCAR GASSETT, OF BOSTON, MASSACHUSETTS.

SAFE.

SPECIFICATION forming part of Letters Patent No. 326,424, dated September 15, 1885.

Application filed January 8, 1885. (No model.)

To all whom it may concern:

Be it known that I, OSCAR GASSETT, of Boston, county of Suffolk, and State of Massachusetts, have invented an Improvement in 5 Safes, of which the following description, in connection with the accompanying drawings, is a specification, like letters on the drawings representing like parts.

This invention, relating to safes and vaults, 10 has for its object to increase the difficulty of, if not absolutely prevent, burglars or unauthorized persons from picking or opening the usual permutation-locks thereon.

An experienced person having very acute 15 sense of hearing or of touch, or both, is often enabled to effect entrance into a safe or vault, for with such senses highly developed the exact position of the parts of the lock mechanism may be accurately ascertained or defined.

20 In every permutation-lock there are a certain number of combinations, and if time permit the opening of the lock, everything being in perfect condition, is but a mathematical problem. I have ascertained by experiment that 25 the sense of hearing and of touch never so acute are rendered entirely unavailable provided a noise, hammering, or vibration is kept up in the safe or vault while the knob-spindle of the lock is being tampered with; and, 30 to effect the greatest amount of vibration or trembling movement to the knob-spindle, I prefer that the blows of a hammer within the safe be made effective against the said spindle, and by causing the spindle and lock to vibrate 35 at such time the tumblers of the lock are made to vibrate or tremble sufficiently to cause any tumbler brought into supposed correct position for trial with other tumblers to be jarred out of place while the second or third are being 40 brought into trial position in usual manner by the knob-spindle. In order that such movement of the tumblers may not interfere with the operation of the lock by authorized persons at the proper times or during business 45 hours I have provided a time mechanism whereby the vibrations of the hammer or the noise within the safe or vault may be automatically stopped after the passage of any predetermined number of hours after closing the 50 safe or vault door.

My invention consists, essentially, in the combination, with a safe or vault and its door, having a lock, of a hammer or striking mechanism, and with means to actuate the said hammer or striking mechanism, whereby a jar 55 is produced at that part of the door occupied by the lock and to the lock itself, and preferably the blows of the hammer or striking mechanism are made effectual at the inner end of the knob-spindle, at the back of the lock, or 60 at the inner side of the door. The hammer shown in this instance of my invention is carried by an armature of an electro-magnet located within the safe or vault, together with a battery, the magnet being in a circuit so arranged 65 as to be partially controlled by shutting the door of the safe or vault, the circuit being preferably completely closed only while the knob-spindle is being turned after locking the safe.

70 Figure 1 is a cross-section of a part of a safe or vault with its door closed, the door being supposed to have upon it a permutation-lock of usual construction, the hammer and means for operating it and vibrating or jarring the 75 usual knob-spindle being shown in plan view. Fig. 2 is a detail showing the electrical connections and circuit-controlling device in plan view; Fig. 3, a section of the lock-spindle detached, it having attached to its inner end 80 a circuit-controlling device or clamp; Fig. 4, a detail of the said circuit-controlling device and the plan of connecting it with the spindle frictionally, and Figs. 5 and 6 details showing the detent of the time-motor and 85 circuit-controlling device governed by the said motor in front and rear elevation, respectively.

80 In the drawings, A represents the body of the safe or vault; A', its door, hinged at A' in usual manner; and B is the knob-spindle of the lock, it passing through and being shaped and adapted to operate the tumblers of any usual or suitable permutation-lock, the latter not being herein shown in detail; for, to obtain 90 a correct idea of my invention, it is necessary only to show the knob-spindle, and it will be understood that the particular construction of the lock and of the tumblers is immaterial 95 so long as the lock is of that class in which 100

several tumblers must be brought into certain exact position before the bolt of the lock can be reciprocated. In all such locks as known to me the inner end of the knob-spindle may 5 be seen at the back of the lock or at the inner side of the door, the inner end of the knob-spindle, in most instances, being covered by a plate attached to the back of the lock by screws or bolts.

10 In accordance with my invention, the plate referred to will be removed, or a hole will be cut through it opposite, and so as to expose the inner end of the knob-spindle, so that it may receive against it blows of a hammer or vibrator.

15 As herein shown, the spindle is made in two pieces, its inner end being made or shaped like a cap-screw, B', having a shoulder, 20, and a head, 30, the screw forming the inner end of 20 the knob-spindle or a rigid metallic part of it, and when in place, as in the drawings, serving to hold a slotted metallic arm, b. (Shown best in Figs. 3 and 4.) The arm b is moved with the knob-spindle frictionally as the latter is rotated, the said arm moving with the knob-spindle until it meets one or the other of the 25 circuit-closing points b' b², constituting one terminal of an electric circuit, of which the arm b is the other terminal, so that when the 30 said arm meets the said points it closes the said circuit, and the arm remains in contact with the said circuit-closing point or stop in the further movement of the spindle, which then turns frictionally within it. The electric circuit controlled by the said arm and points, 35 which constitute a circuit-closer therefor, includes an electro-magnet, M, of usual construction, located in the safe or vault on a suitable support. The screw d¹⁰, extended through 40 both branches of the arm, forms an adjusting device, by which the arm b may be made to embrace the knob-spindle or its screw terminal more or less closely.

The armature M' of the magnet M is provided at its free end with a hammer, M², which as the armature is attracted is thrown toward the knob-spindle B; but herein, instead of the hammer striking directly against the spindle B, I have interposed between the said spindle 50 and hammer a rod, d, which is placed in suitable bearings, d' d², and is surrounded by a coiled spring, d³, which latter normally acts to keep the said rod in contact with the end of the spindle, the rod d forming practically a stiff 55 metallic continuation or prolongation of the inner end of the spindle, so that the blows of the hammer against the rod are as effectual in vibrating the spindle as were the hammer to strike directly against the inner end of the 60 spindle, the employment of the rod being desirable, chiefly, to reduce the cost of the construction of my apparatus.

65 The armature is acted upon at its back by a contact-spring, e, held by an insulated post, e', in the circuit of the magnet, as is usual in electrically-operated vibrators for bells.

The arm b is provided at its rear side with

two pins, b⁴, (see Fig. 3,) between which is placed the free end of a spring, b⁵, (see Fig. 2,) attached at its upper end to the door by a screw, c, the said spring, by its action against the pins b⁴, serving to remove the arm after the spindle is disengaged by the operator to an intermediate position between the points b' and b², the movement of the arm b by the 75 spring acting to break the circuit and leave the armature at rest.

The magnet might be operated to vibrate the hammer continuously; but such embodiment of my invention would result in useless 80 waste of battery-power. All that is necessary is that the hammer operate to vibrate or jar the spindle only when the lock is being tampered with out of time or by an unauthorized person, and so I have provided the knob-spindle with the arm b, in order that the electric 85 circuit, to effect the operation of the magnet and its hammer, may be closed by the said arm only when the spindle is being operated or turned to bring a tumbler into place, and the 90 circuit to operate the armature and hammer will be made whichever way the spindle may be turned.

The apparatus herein described needs to protect the safe or vault lock in practice for not 95 over forty hours continuously, as that is about the maximum time that a bank-vault is ever closed legitimately—as over Sundays or holidays—so in the circuit of the magnet I in practice employ a time mechanism to control the circuit, and thereby prevent the operation 100 of the magnet and hammer or vibrator after a certain length of time.

The circuit-wire 2, leading from one pole of the battery G, is connected with the magnet M, 105 from which the circuit is continued by wire 3 to the armature M, the back contact-spring, e, of which is connected by wire 4 to one member, f', of a circuit-closer, the other member, f, of which is connected by wire 5 with the two contact-points b' b², while the other pole of the said battery is connected by wire 6 with a spring, 7, which makes contact with the knob-spindle and arm b when the door is closed. The said circuit-closer f f' is controlled by a clock-work 115 or motor g, adapted to run fifty hours or more, actuating a disk, g', arranged, as shown in this instance, to make one complete rotation in forty-eight hours. The said disk is provided with a series of holes, g²—shown as six in number—so that the disk will occupy eight hours 120 in turning through the space between two of the consecutive holes, which are adapted to receive a pin or stud, g³, which projects from both sides of the said disk, the part projecting 125 at the rear side, as shown in Fig. 6, being adapted at one point in the rotation of the disk to engage the member f' of the circuit-closer and separate it from the member f, thus opening the circuit of the battery B and magnet M, and 130 causing the hammer M² to cease operating, even when contact is made between the arm b and points b' and b², so that the safe may be easily opened by authorized persons at the

proper hour; or in case an accident should happen to the lock, requiring the services of an expert to open it, he will not be embarrassed by the operation of the hammer. The part of 5 the pin g^3 projecting at the other side of the disk constitutes a stop for arresting its movement when in the position to thus open the circuit-closer, the said stop being engaged by a detent, i , pivoted on an arm, i' , itself pivoted 10 on the frame-work of the motor g , and having a movement between stop-pins i^2 i^3 . (See Fig. 5.) The arm i' is acted upon by a spring, i^4 , tending to give the detent i a movement in opposition to the pressure of the stop 15 g^3 thereon, but not sufficient to overcome the said pressure, so that when the motor is arrested the detent comes to rest with the arm i' resting against the stop i^2 , and when the detent is momentarily disengaged from the stop 20 g^3 the spring i^4 will throw it above the stop, so that it will not engage the stop if immediately thrown back by the spring i^5 .

A second pin, similar to the one g^3 , will be provided, which before closing the safe at 25 night will be placed in one of the holes g^2 , according to the length of time that the safe is to remain locked and the hammer M^2 in operation. For instance, if it is to remain locked for sixteen hours, the usual interval from the 30 close of one business day to the beginning of the next, the pin will be placed in the second hole from the pin engaged by the detent, and then when the stop is released by the disengagement of the detent upon the closing of the safe- 35 door, as hereinafter described, the motor will run for sixteen hours and then be arrested by the second pin; but if the safe is to be closed over a whole day and night, as at the end of a week, the second pin will be placed in the 40 fifth hole and forty hours will elapse before the circuit is again broken.

The circuit-closing springs f f' will preferably be connected with the safe-door rather than with the frame-work of the motor g , so 45 that in the event of the said motor becoming shattered or broken by the operation of burglars the circuit will still remain closed and the hammer c in operative condition.

The detent i is disengaged from the stop to 50 release the motor by a shoulder, p , of a slide-piece or tripping-rod, p' , extending through or along the door of the safe, and normally when the door is open projecting from the hinged end of the door, so that when the door 55 is closed the said slide-piece will have a longitudinal movement, forcing the shoulder p against the detent i or a projection, i^6 , thereon, and thereby disengaging the detent from the stop g^3 , when the spring i^4 immediately 60 throws the detent upward, so that the said stop g^3 will not be engaged by the detent i , although the latter returns immediately under the action of the spring i^5 to the proper position to engage the next stop when it arrives 65 at the detent in the rotation of the disk g .

The tripping-rod p is guided in its longi-

tudinal movement by a pin, r , against which it is held by a spring, p^2 , which permits the said rod to yield laterally, so as to allow the shoulder p to pass the projection i^6 on the detent-lever in the return movement of the rod caused by the spring p^4 when the safe-door is opened. 70

As herein shown, the contact-spring 7, together with the magnet and battery, is supported on a portion of the interior frame-work or finish in the body of the safe, while the time-movement g is supported on the door, the portion 4 of the circuit extending from the said magnet to the said time-movement being 80 flexible or jointed at the hinge of the door or other point to accommodate the movement of the latter, the circuit being open between the arm b and spring 7 when the door is open and being connected at this point when the door is 85 closed.

A circuit-closer controlled by the knob-spindle of a lock, as herein shown, in such manner that the circuit is normally in one condition while the said knob-spindle is at 90 rest, and in another condition when the said knob-spindle is being turned, may be employed for other purposes than for controlling the circuit of a vibrating hammer, as herein shown—such, for instance, as for controlling a circuit leading to distant station, and governing the operation of signaling apparatus to indicate any tampering with the said circuit. 95

The hammer M^2 is insulated from the armature-lever M' to prevent the completion of a short circuit for the battery when the said hammer is in contact with the rod d . 100

I claim—

1. The combination, with a safe, of a hammer, electro-magnet for vibrating the same, and battery and circuit for said magnet, substantially as and for the purpose set forth. 105

2. The combination, with a safe, of a hammer, electro-magnet for vibrating it, and a battery and circuit for the said magnet and circuit-controlling devices, governed by the movement of the safe-door, substantially as described. 110

3. The combination, with a safe, of a hammer, an electro-magnet for actuating it, a time-movement governing the circuit of the said magnet, and a detent for the said time-movement, operated by the movement of the safe-door, substantially as described. 115

4. The combination of the spindle of a lock with a hammer or vibrator and with means to actuate the same to vibrate and jar the spindle, substantially as described. 120

5. The combination, with the spindle of a lock, of a hammer or vibrator, an armature, and magnet to effect the movement of the hammer or vibrator, substantially as described. 125

6. The spindle of a lock, its frictionally-held arm and contact-points in circuit with a magnet, combined with a magnet and vibrator provided with a hammer, whereby the 130

hammer will be operated to vibrate the spindle while the latter is being rotated, substantially as described.

7. A safe or vault having a hinged door and a lock thereon provided with a spindle, the inner end of which is exposed or prolonged, combined with a circuit-closing spring located in the safe, the said spring being placed in position to be acted upon by the inner end of the spindle of the lock when the door is closed, substantially as and for the purpose described.

8. The combination of the knob-spindle of

a safe or vault lock with a circuit-controlling device connected with the said spindle, by which the condition of an electric circuit is changed while the said spindle is being turned, substantially as described.

In testimony whereof I have signed my name to this specification in the presence of two subscribing witnesses.

OSCAR GASSETT.
